CLAIM

The ornamental design for a laptop computer, as shown and described.

DESCRIPTION

FIG. 1 is a front, right side, perspective view of a laptop computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side perspective view in an opened state thereof;

FIG. 9 is a front view in an opened state thereof;

FIG. 10 is a rear view in an opened state thereof;

FIG. 11 is a left side view in an opened state thereof;

FIG. 12 is a right side view in an opened state thereof;

FIG. 13 is a top view in an opened state thereof; and,

FIG. 14 is a bottom view in an opened state.

(Continued)

The broken lines showing portions of the laptop computer are included for the purpose of illustrating portions of the article and form no part of the claimed design.

1 Claim, 14 Drawing Sheets
